UNITED STATES PATENT OFFICE

2,440,408

SHIP HULL CONSTRUCTION

Arthur H. Lackie, Duluth, Minn.

Application August 4, 1944, Serial No. 548,051

1 Claim. (Cl. 114—79)

1

This invention relates to metal ship hull construction. The possibility of dangerous fracture in a poorly welded or riveted joint of a marine ship's hull of modern construction, as well as in the skin proper of the hull, is well known to those versed in the arts of both shipbuilding and maritime navigation.

To reduce to a minimum such danger is the principal object of the instant invention.

Another object is to provide a suitable type of expansive joint for such purpose.

Still another object is to so position such joints in the hull of a ship as to derive the best possible safety results therefrom.

Other objects and advantages may appear in the further description of the invention.

Referring now to the drawings, forming part of this application, and in which like reference numerals indicate like parts:

Fig. 1 is an enlarged thwartship sectional view of a ship's hull, looking forwardly therein,

Fig. 2 is a diagrammatic plan view of the interior frame and shell structure of a common steel ship hull, except at the forward starboard curved quarter thereof, where an improved installation of shell framing is illustrated, and

Fig. 3 is a part sectional and elevational view of one form of expansive joint deemed practical for the purpose described.

As is well known, the many different types and shapes of ship hulls vary greatly in their interiorly located more rigid frame structure, said structure usually including both fore and aft and thwartship girders as well as bulkheads that are rigidly united and in much less need of expansive or yieldable connections, one reason being that said frame structure is more usually subject to a uniform temperature than the skin or shell structure, which latter is more subject to varying temperatures and especially the upper parts thereof. The inner structure has a substantially constant temperature the year around, while the shell structure is subject to changes varying from, say, —40 degrees Fahrenheit to 120 degrees Fahrenheit.

In the drawings, 1 represents the skin or metal shell plating of the hull of a common marine ship or vessel, and 2 the vertically disposed side frame members to which the shell plates are either welded or riveted, the former now almost universally practiced in shipbuilding.

In Fig. 2 I have illustrated diagrammatically the more rigid and substantially rectangularly shaped interior frame structure of the hull of an ordinary vessel, the fore and aft girders being

shown at 3—3, and the thwartship girders or bulkheads being shown at 4—4.

It is well known that in uniting two or more metal plates, either by riveting or welding, care must be taken to bolt or tack them firmly in their ultimate desired relationship, and as nearly as possible in their natural preformed shape so as to avoid abnormal stresses by expansion and/or contraction as the union of parts progresses, this being a well known requisite in ship hull construction to avoid as much as possible unequal or opposed stresses especially in the shell of the hull so subject to varying temperatures in different climates and circumstances.

15 If the hull of a vessel is not so properly constructed, and experiencing at all normal times more or less strains and stresses due to improper union of parts, especially in the shell portions thereof, then obviously under further unequal 20 stresses, due to changes in temperature, when such warping shell is rigidly fixed to the unyielding interior frame structure, fracture is liable to occur resulting in serious damage, or worse.

Undoubtedly, practically all metal hulls are 25 subject to fracture due to unequal stresses of this character, and to avoid same, I propose to provide suitable expansive joints or connections for installation at the four most vital parts of a ship's hull to wit: the two forward major opposed portions 30 5 and 6, and the like after opposed portions 7 and 8.

One type of joint deemed practical for such purpose is shown in Fig. 3 of the drawings, and 35 may be aptly called a hydraulic expansive joint, comprising a cylindrical unit such as indicated at 9 and rigidly fixed to one end of one of the thwartship girders as indicated at 10. This cylinder is formed with the chamber 11 in which is 40 mounted the reciprocal piston 12 fixed to the innermost end of the piston rod 13, and the opposite end of the piston rod is pivotally mounted upon the through pin 14 supported between a pair of suitable brackets 15 fixed to the inner edge of the side frame member 2, and to the outer edge 45 of said frame member is fixed thereto the skin or shell 1 of the hull.

Within the chamber 11 of the member 9, and 50 between the head of the piston 12 and the opposite end of the chamber is installed the suitable expansive helical spring 16 for the purpose of counteracting the normal inward pressure against the shell of the ship caused by the varying hydrostatic head of the water therewithout. The chamber 11 is so connected with the excess reservoir 17 of oil being used in the cylinder to insure

adequate supply, by gravity, for same against any possible leakage, and to compensate for the varying capacity of the chamber upon the pitman side of the piston. The piston 12 is provided with a comparatively small relief hole through the upper portion as indicated at 18 so that the pressure of the oil is automatically gradually equalized on both sides of the piston, with the reservoir being exposed to atmospheric pressure. The small through relief hole 18 is spaced materially from the inner surface of the cylinder to prevent its being clogged by any possible foreign matter in the oil. Thus, obviously, there is provided an extremely gradual yieldable connection of the united parts.

It will be noted that provision may be made for auxiliary vertical support, if necessary, for that portion of the interior frame structure of the hull indicated by the thwartship girders 10 by a protruding extension as indicated at 19 which is made to overlap and slidably rest upon the upper surface of the brackets 15 as relative movement of the parts take place.

Thus is provided one form of yieldable hydraulic means for connection between the interior structure of the vessel and the shell framing thereof, but forming a substantial, dependable union of same.

It is to be noted that one of the principal features of the instant invention is the novel location of such a joint in an ordinary ship's hull, to wit: the four vital major curved portions referred to above.

In the cross sectional view, Fig. 1, taken just abaft the major arcuate portions of the bow of the hull, the shell framing is suggested as at 2—2 on both sides thereof as well as the forecastle bulkhead 20 which is found in some types of vessels. Upon the left side of said view is illustrated the common manner of permanently fixing the deck frames 21 of the between deck and 22 of the main deck, while at the right side of said figure is illustrated, as by arrowheads, approximate location of proposed expansive joints, that is, illustrative of suitable location where expansive

joints may be installed and result in maximum efficiency of protection of the entire hull structure. At 23—23 are illustrated fore and aft girders, or such locations may be occupied by vertical stanchions, or the like, forming part of the interior frame work as described.

In Fig. 2, and at the foremost starboard quarter of the hull illustrated, I have shown the shell framing 2 as extending inwardly as nearly as possible perpendicularly to the arc in the shell 1 of the hull instead of directly across same as shown upon the opposite side of the hull and which may be preferable to the latter in some instances.

Having thus described my invention, what I claim and desire to secure by Letters Patent is:

In an expansive joint for ship hull construction having side frames and thwartship internal girders; an inwardly projecting flat topped bracket fixed to one of said side frames carrying a piston rod pivotally mounted on said bracket, an elongated flat extension member fixed adjacent the end of one of said girders with its free end resting upon the flat surface of said bracket, a cylinder fixed to the end of said girder carrying a piston therewith cooperatively engaged with said piston rod, and a fluid supply for said cylinder.

ARTHUR H. LACKIE.
